UNITED STATES PATENT OFFICE.

WILLIAM SPENCER BOWEN, OF NEW YORK, N. Y.

STEAM GENERATOR.

1,415,778.

Specification of Letters Patent. Patented May 9, 1922.

Application filed February 16, 1920. Serial No. 359,080.

To all whom it may concern:

Be it known that I, WILLIAM SPENCER BOWEN, a citizen of the United States, residing at New York, in the county of New York and State of New York, have invented new and useful Improvements in Steam Generators, of which the following is a specification.

My invention relates to a steam generator. According to the ordinary methods for generating steam, the water to be vaporized is separated from the fuel by the interposed boiler plates forming the shell, fire-box, flues and tubes. These usual methods or systems attempt to avoid high temperatures such as are used in my apparatus, because above certain temperatures a layer of steam forms between the boiler plates and the water so that the temperature of the plates ceases to be controlled by the boiling point of water. At high temperatures the plates may assume the temperature of the hot gases of the fire-box, and soon pass beyond the limits allowed for expansion with the result that buckling and finally melting of the plates ensues.

According to my invention, high temperatures are desired and temperatures in excess of the melting point of iron are employed. These high temperatures are used because the method of heat transfer is primarily that of radiation and radiant energy varies as the fourth power of the absolute temperature. Therefore from the standpoint of efficiency it is important to maintain high temperatures.

The accompanying drawings illustrate a device which embodies the principal features of my invention.

In the drawings Fig. 1 is a vertical section of a steam generator constructed in accordance with the principles of this invention.

Fig. 2 is a section on the line A—A of Fig. 1.

Fig. 3 is a section on the line B—B of Fig. 1.

Fig. 4 is a partial vertical section of a modified form of my device.

Fig. 5 is a section through one of the spark screens in Fig. 4.

Fig. 6 is a side view showing the platinum points and insulator of one of the spark screens.

The numeral 3 designates the casing or jacket of the steam generator which is

formed internally with the spirally arranged passage 14, starting with the water inlet 2 and ending at the opposite end of the generator in the restricted steam orifices 10. 60 A steam outlet pipe 1 communicates with the interior of the jacket 3, one end of said pipe being shown in the drawing. The other end of the jacket is formed with an opening for receiving a threaded bushing 12, 65 which is also provided with a central opening for receiving the threaded end of the air pipe 7. To the latter pipe 7 is connected a fuel pipe 9 through which fuel is admitted to form with the air a suitable combustible 70 mixture for burning within the generator.

The pipe 7 is preferably made of some infusible material such as porcelain, quartz, or an infusible earth. The inner end of the pipe 7 opens into an infusible tube 7¹ which 75 extends through the greater portion of the length of the jacket. The inner tube 7¹ has lugs 6 projecting therefrom to support the tube against the walls of an outer tube 7¹¹ and afford a sliding fit to allow for expansion. 80 The porcelain tubes 7¹ and 7¹¹ are shown as integral at the base portion 11, the outer tube being provided with a series of holes near the base portion so that the fuel mixture after traversing the inner tube and 85 returning through the space between the two tubes, may have access to the spark plug 8 adapted to function to initiate the burning of the fuel mixture.

The base of the porcelain tubes is held in 90 the water jacket by the bushing 12 and the top is supported by the porcelain cap 13. The cap 13 has a solid body overlying the open ends of the tubes 7¹ 7¹¹ from which extend lugs 15 that embrace the circumference 95 of the outer tube but are in spaced relation so as to permit the passage of all gases and at the same time furnish bearing surfaces on the tube 7¹¹ and the interior of the outer jacket. 100

When lighted by the spark plug the fuel mixture burns with a steady flame in the annular space between the first and second infusible tubes. These tubes become incandescent and radiate heat to the water jacket 105 walls 3.

The water jacket 3 is preferably made of cast iron as shown but non-fusible material could also be used. In the latter case a surrounding steel sleeve (not shown) would 110 be employed to take the pressure. Outside the water jacket an asbestos envelope 4 is

provided to prevent loss of heat due to the radiation of conducted heat.

Gas or fuel oil is admitted at 9 and air at 7. In case a carbureted mixture under pressure is used one of the pipes 7 or 9 may be omitted, as is well understood. The water jacket 3 is heated primarily by radiation from the incandescent porcelain tubes. The feed water passing through the spiral passages of the jacket 3 is preheated to a high temperature and enters the annular space between the outer tube and cylindrical wall of the jacket through the restricted orifices 10; the reduction in pressure in passing through these orifices causing the water to flash into steam. In its passage through the outer annular space to the outlet pipe (1) the steam is superheated. Practically no heat is transmitted by the water jacket due to the asbestos insulation.

It will be understood that the outlet pipe may contain a valve for controlling the passage of the steam and gases to an engine, or the like, and also that the water and fuel mixture may be automatically or manually controlled but these features do not enter into my invention and consequently have not been shown or described.

In Fig. 4 is shown a modified form of my invention in which the superheated steam and products of combustion are passed through a series of spark screens. In this case the water jacket 3 is preferably formed with a straight passage and is prolonged beyond the tubes 7¹, 7¹¹ the outer tube being formed with a deflecting end 16, and with supporting lugs 17. Insulators 18 are inserted through the jacket at intervals and these insulators contain the conductors 19 that terminate in platinum points 20. These conductors are arranged in a periodically interrupted electric circuit containing an induction coil (not shown) so that sparks will pass through the gap formed between the platinum points. The steam and gases after passing the last spark screen escape through the outlet pipe 21. The jacket is shown protected by the surrounding heat insulating material 22. Some of the water particles in flashing into steam under the high temperature that exists in the interior of the generator are broken up into the elements hydrogen and oxygen; the hydrogen remaining in its nascent state until it reaches the spark screens. The carbon of the hydrocarbon fuel will combine with the oxygen of the air or decomposed steam and the nascent and incandescent hydrogen will combine with the free and incandescent nitrogen to form ammonia (NH₃). The use of the electric spark modification of this invention is to augment this latter action. After using the gases and steam expansively in the engine the ammonia may be recovered in a number of ways, as by solution in water.

Having thus described my invention what I claim and desire to secure by Letters Patent is as follows:

1. A device for developing energy comprising a water jacket, formed at one end with restricted orifices, insulating material surrounding said jacket, infusible burner tubes adapted to be heated to high temperatures located within the jacket, whereby the water in passing through the jacket is heated above the temperature of vaporization at the pressure prevailing on the interior of said jacket and flashes into steam on passing through said orifices.

2. A device for developing energy comprising a casing provided with a water jacket, heat insulating material surrounding said jacket, infusible burner tubes located within the jacket, said casing having apertures therein forming communication between the water jacket and the space between said tubes and casing, means for supplying a combustible mixture under pressure to said tubes, and a spark plug secured to the casing for initiating the burning of said mixture, whereby said tubes are heated to incandescence and the water passing through said apertures is converted into steam by the heat radiated within the jacket.

3. A device for developing energy comprising a casing provided with a water jacket, heat insulating material surrounding said casing, infusible inner and outer burner tubes located within the casing, said casing having apertures affording communication between the water jacket and the space between said tubes and casing, a bushing secured to the casing for supporting one end of said tubes, means for supplying a combustible mixture to the inner tube, and a cap supporting the other end of the outer tube within the jacket and adapted to move relatively to said jacket to allow for the heat expansion of said tubes.

4. A device for developing energy comprising a water jacket having a restricted exit opening formed in one end thereof, heat insulating material surrounding said jacket, burner tubes supported centrally within said casing having outlet openings in proximity to said orifices, means for supplying a combustible mixture under pressure to said tubes for heating the same to a high temperature and an outlet pipe for the steam and products of combustion at the end of said jacket opposite from the orifices whereby the steam is superheated in its passage through the interior of the jacket.

5. A device for generating energy comprising a water jacket and a heater centrally supported within the jacket providing an annular space therebetween whereby the water within the jacket is heated by radiation and absorption, said jacket having

- orifices at one end communicating with said annular space, an outlet pipe for the resulting steam and products of combustion and means interposed in the path of the steam and combustion products for causing the combination of nitrogen and hydrogen to form ammonia.
6. A device for generating steam comprising a water jacket and a heater on the interior thereof, means for supplying fuel atomized by air under pressure to said heater, insulating material inserted through said jacket and electrical conductors passing through said insulation for forming spark gaps in the path of the steam and products of combustion to cause the combination of hot nascent hydrogen and the nitrogen of the atomizing air.
7. A device for generating energy comprising a water jacket formed in a casing, burner tubes located within the jacket in spaced relation to the side walls thereof, means for conducting fuel atomized by air under pressure to said tubes for igniting and burning therein and heating the tubes to a high temperature, said water jacket communicating with the hot interior of the casing through restricted apertures formed therein, whereby some of the water is decomposed on entering the casing so as to free nascent hydrogen, and means in said casing for promoting the combination of said nascent hydrogen and the nitrogen of the atomizing air.
8. A device for generating energy comprising a casing, a heater located in said casing in spaced relation to the side walls thereof, means for conducting a combustible fuel and air mixture to said heater, means for introducing water into the highly heated interior of the casing whereby said water is converted into steam, and means in said casing for subjecting the products of combustion and steam to electric discharges and in conjunction therewith to the influence of radiant heat from said heater.
9. A device for developing energy comprising a casing provided with a water jacket, heat insulating material surrounding said jacket, infusible inner and outer burner tubes within the jacket, said outer tube being of greater length than the inner tube, a bushing secured to the casing for supporting one end of said tubes, said casing having apertures at one end for affording communication between the jacket and the space between the outer tube and the casing, means for supplying a combustible mixture to the inner tube, a cap supporting the other end of the outer tube adapted to form a closure therefor and direct the combustible mixture into the space between said tubes, lugs formed on said inner tube and adapted to have sliding contact with said outer tube and spaced lugs formed on said cap adapted to have sliding contact on the interior wall of said casing, and a steam outlet passage at the end of the casing opposite from said apertures whereby the steam and the products of combustion resulting from the burning of the combustible mixture may pass through the space between the outer tube and casing, be subjected to the heat from the incandescent tubes and escape through said outlet.

In testimony whereof I have hereunto set my hand in presence of two subscribing witnesses.

WILLIAM SPENCER BOWEN.
